UNITED STATES PATENT OFFICE.

MORTON EARLE MYERS, OF NEW YORK, N. Y., ASSIGNOR, BY MESNE ASSIGNMENTS, TO
JAMES A. ABELES, OF NEW YORK, N. Y.

DIAPHRAGM-HORN.

1,251,270.

Specification of Letters Patent. Patented Dec. 25, 1917.

Application filed March 5, 1912. Serial No. 681,752.

To all whom it may concern:

Be it known that I, MORTON EARLE MYERS, a citizen of the United States, residing at the borough of Manhattan, in the city, 5 county, and State of New York, have invented certain new and useful Improvements in Diaphragm-Horns, of which the following is a specification, reference being had therein to the accompanying drawings, 10 which form a part thereof.

My invention relates to diaphragm horns, and more particularly to a type wherein rotary movement is imparted to the striker member by a reciprocating actuating stem 15 which, when the horn is mounted upon a vehicle, will be conveniently accessible to the chauffeur. The actuating stem imparts a rotative movement to the striker member and is automatically restored to normal 20 without interfering with the continued rotation of said striker member under momentum, and without a rotative movement of said actuating stem.

The main object of my invention is to 25 provide a horn of this character wherein the desired frequency of diaphragm vibrations may be secured by the movement of the actuating handle through a convenient distance and without the necessity of employing any multiplying gearing, auxiliary 30 shafts, or rotating parts, other than the diaphragm actuating member and the parts coaxial therewith.

In my improved construction, the striker 35 member, or diaphragm-actuating cam, is mounted to rotate about an axis parallel to the diaphragm and a manually movable member is mounted to move downward vertically in a direction also parallel to the dia- 40 phragm. The direct coaction of the downwardly movable manually-actuated member and the support for the rotor causes the rotation of the rotor without the interposition of multiple gearing. These directly co- 45 acting parts for converting the reciprocating into rotary motion may be varied within the scope of the appended claims without departing from the spirit of my invention. They permit a great reduction in the num- 50 ber of parts and the cost of manufacture and assembly, and cannot readily get out of

order. At the same time, they readily permit the continued rotation of the rotor under its own momentum during the return movement of the manually actuated reciprocating member, which latter movement is preferably accomplished by a suitable spring.

As one important feature of my invention, I utilize a worm and nut relatively 60 movable axially, one being connected to the handle and the other to the rotor. In the preferred construction, the worm is rigid with the rotor and constitutes the shaft thereof and the nut is held against rotation 65 when moving along the worm in one direction and is allowed free rotation when moved in the reverse direction.

As an important feature of my invention, I make the rotor of dished form with the 70 toothed portion at the periphery lying in a plane diametrically of the diaphragm for engagement with a wear-piece at the center of the diaphragm. The center of dished portion of the rotor is at one side of the 75 plane of the toothed portion, whereby the actuating mechanism may have a greater range of movement by entering the dished portion and without necessitating any enlarging of the size of the casing containing 80 the operating parts.

Referring to the drawings:—

Figure 1 is a vertical section of a horn embodying my invention;

Fig. 2 is a horizontal section of the striker 85 member and its actuating means; and

Fig. 3 is a detail view of the nut co-operating with the worm for actuating the striker member.

Like letters refer to like parts throughout 90 the several views.

In the form of my invention shown in the accompanying drawings, *a* indicates a horn casing having an ordinary sound outlet opening *b* in communication with an ordinary amplifier *c*. Mounted within said casing by means of a metallic disk *d* having a central opening *d'*, is a diaphragm *e* having a stud *e'* centrally thereof and projecting partially through said opening *d'*. Carried 95 by the disk *d* is a bracket *f* projecting from a point eccentrically of said diaphragm and

perpendicular to the normal plane thereof, which bracket is adapted to support a rotary striker member g , the rim of which is provided with a plurality of contacts g' adapted to pass through the opening d' and contact with the stud e' to flex the diaphragm when said striker member is rotated.

The striker member g has a cup-shaped portion g^2 adapted to form a spring chamber therein, and extending axially of said striker member and carried thereby is a worm shaft h , this shaft extending perpendicularly of the axis of the diaphragm, thus permitting the application of power to the striker member in a line at right angles to the direction in which it is desired to project the sound waves. This construction is desirable as permitting the convenient application of manual power to the horn, and the application of such power in a line which will permit the development of the desired speed and duration in the rotation of the said striker member with the smallest expenditure of energy by the chauffeur.

To insure the application of power in an equal degree upon both sides of the said worm shaft h , I provide this shaft with a plurality of similarly pitched threads h' and h^2 , starting at diametrically opposite points.

Slidably mounted upon the said shaft h is a nut i having diametrically opposite interior teeth i' adapted to coöperate with the threads h' and h^2 respectively, which nut is acted upon by a helicoidal spring j gradually reduced in diameter toward the nut i , so as to cause the coils thereof when tensioned to nest one within the other and thus place no substantial limitation upon the quantity of movement of said nut in actuating said striker member.

The cupped portion g^2 of said striker member and the construction of said spring afford the requisite clearance to permit that movement of said nut necessary to impart to said striker member movement of sufficient duration to develop a signal of the desired length.

The spring j has for its sole function the restoration of the nut i to normal, so that it does not add materially to the load in actuating the horn.

The worm shaft h is attached to the striker member g at the bottom thereof and projects below said member in a manner to form a bearing h^3 for the shaft h , adapted to rotate in a bearing f' in the bracket f , the lower end of said shaft being provided with a cone k . About the bearing f' on both sides thereof, the bracket f is beveled as shown, and seated between the upper beveled edges and the cup g^2 , and between the lower beveled edges and the cone k are pluralities

of balls encircling and bearing upon the 65 bearings h^3 of the said shaft h .

This construction affords not only a ball bearing for the striker member, but also an extended bearing which will tend to prevent any play of the striker member sufficient to vary the normal relation of the contacts g' thereon and the diaphragm stud e' .

Inclosing the striker member is a housing m having in the top thereof and alined with the shaft h a bearing post n in which is 75 slidably mounted a stem o . This stem and the bearing therefor are preferably flattened at one point thereof so as to prevent rotation of said stem, the stem itself being hollow so as to permit it to telescope upon the 80 worm shaft h .

The periphery of the nut i is provided with ratchet teeth i^2 as shown, and said nut is held against rotation in one direction by means of a spring pressed pawl p mounted 85 in a bracket q carried by the stem o , this pawl being so set as to hold said nut against rotation when it is depressed while permitting it to rotate freely when it is permitted to rise under said spring j .

The operation of the herein described horn is substantially as follows:

When it is desired to sound an alarm signal, the stem o is forced downwardly by the hand or foot of the chauffeur, with sufficient force to develop high velocity in the striker member g . When depressed, this stem carries with it the nut i which is held against rotation by the pawl p during its descent, the force applied to the stem o being thus 100 directly applied to rotate the shaft h and with it the striker member g and impart to the diaphragm e a sequence of impulses or flexures which will develop the requisite sound waves. The spring j will be placed 105 in tension by the nut i .

The use of a plurality of worms at diametrically opposite points results in the equal application of power upon both sides of the shaft h and thus minimizes or eliminates any tendency of the nut i to bind upon said shaft.

As the stem o descends, it will telescope the shaft h , and thus permit the nut i to be forced within the cup g^2 until said nut is 115 substantially coincident with the bottom of said cup.

When the stem o is released or reaches the limit of its direct reciprocation, the nut i will rotate freely with the shaft h thus permitting the striker member to overrun under its momentum, and limiting the resistance encountered thereby at any point to the friction between it and the stud e' . As the stem o is released, the spring j will force 125 the nut i and with it the stem o upwardly to their normal positions, the nut i turning freely with or upon the said shaft h .

The flattened portion of the stem *o* prevents any rotation of said stem, thus limiting its movement to a reciprocatory movement only.

5 By arranging the parts as shown, the amplifier *c* may be projected toward the front of the vehicle, and the stem *o* may be directed vertically so that the weight of the chauffeur may be utilized in applying the necessary power to the stem *o* without inconvenience and in a manner to facilitate the application of the maximum power. This feature of permitting the application of power at right angles to the line of projection of the sound waves is of considerable importance, as facilitating the quick actuation of the horn while at the same time permitting the development of that velocity in the rotation of the striker member necessary to develop sound waves of high frequency.

It is not my intention to limit the invention to the precise details of construction shown in the accompanying drawings, it being apparent that such may be modified without departing from the spirit and scope of the invention.

Having described my invention, what I claim as new and desire to have protected by Letters Patent, is:—

1. A diaphragm horn embodying therein a casing having a sound outlet opening therein, a diaphragm mounted in said casing, a rotary striker member the axis of which extends parallel with said diaphragm, a depressible, non-rotary actuating member, means acting to normally raise said actuating member, a worm shaft carried by said striker member, and actuating means carried by, and movable with, said actuating member, and coöperating with said worm shaft, said actuating means being provided with means adapted to impart rotary movement to said striker member upon the depression of said actuating member, and to rotate with said striker member except during such depression of said actuating member.

2. A diaphragm horn embodying therein a horn casing having a sound outlet opening, a diaphragm mounted in said casing, a rotary striker member, the axis of which is perpendicular to the axis of said diaphragm, a worm extending axially of said striker member, a nut coöperating with said worm, means holding said nut against rotation in one direction while permitting it to rotate freely in the other direction, and a depressible non-rotary actuating member controlling said nut whereby the depression of said actuating member will rotate said striker member and flex the diaphragm.

3. A diaphragm horn embodying therein a horn casing having a sound outlet opening, a diaphragm mounted in said casing, a

rotary striker member, the axis of which is perpendicular to the axis of the diaphragm, a worm extending axially of said striker member, a nut coöperating with said worm having ratchet teeth upon the periphery thereof, a depressible non-rotary actuating stem controlling said nut, and a pawl carried by said stem and coöperating with the ratchet teeth upon said nut whereby the depression of said stem will rotate said striker member and flex said diaphragm.

4. A diaphragm horn, embodying therein a horn casing having a sound outlet opening, a diaphragm mounted in said casing, a rotary striker member, having a cup-shaped central portion, the axis of which is perpendicular to the axis of the diaphragm, a worm extending axially of said striker member, a nut coöperating with said worm, spring means to restore said nut to a normal position, and a depressible non-rotary actuating member controlling said nut whereby the depression of said actuating member will rotate said striker member and flex said diaphragm.

5. A diaphragm horn, embodying therein a horn casing having a sound outlet opening, a diaphragm mounted in said casing, a rotary striker member having a cup-shaped central portion, the axis of which is perpendicular to the axis of the diaphragm, a worm extending axially of said striker member and projecting beyond the bottom of said cup-shaped portion, a bracket having a bearing therein adapted to receive said projected end, said bearing having oppositely disposed bevels thereon, a cone carried by the bottom of said projecting end, bearing balls seated upon opposite sides of said bracket and disposed between said bracket and said cup and between said bracket and said cone, a nut slidably mounted upon said worm, and a depressible non-rotary actuating stem controlling said nut whereby the depression of said stem will rotate said striker member and flex said diaphragm.

6. A diaphragm horn embodying therein a horn casing having a sound outlet opening, a diaphragm mounted in said casing, a rotary striker member, the axis of which is perpendicular to the axis of said diaphragm, a worm extending axially of said striker member, said worm having a plurality of threads of similar pitch upon opposite sides thereof, a nut having a plurality of interior teeth coöperating with said threads whereby a binding of said nut is prevented, and a depressible non-rotary actuating stem controlling said nut whereby the depression of said actuating member will rotate said striker member and flex said diaphragm.

7. A diaphragm horn, embodying therein a horn casing having a sound outlet open-

ing, a diaphragm mounted in said casing, a rotary striker member, the axis of which is perpendicular to the axis of said diaphragm, a worm extending axially of said striker member, a nut coöperating with said worm, a housing for said striker member and said actuating member, a flattened bearing in said housing, and an actuating stem similar in configuration to said bearing, mounted therein and controlling said nut whereby the depression of said stem will rotate said striker member and flex said diaphragm.

8. A diaphragm horn embodying therein a horn casing having a sound outlet opening, a diaphragm mounted in said casing, a disk parallel with and spaced away from said diaphragm, said disk having a central opening therein, a stud carried by said diaphragm in alignment with said opening, a rotary striker member, the axis of which is perpendicular to the axis of said diaphragm, a worm extending axially of said striker member, a nut coöperating with said worm, and a depressible non-rotary actuating stem controlling said nut whereby the depression of said stem will rotate said striker member and flex said diaphragm.

9. A diaphragm horn embodying therein a horn casing having a sound outlet opening, a diaphragm mounted in said casing, a rotary striker member having a cup-shaped central portion, the axis of which is perpendicular to the axis of the diaphragm, a worm extending axially of said striker member, a nut coöperating with said worm, spring means to restore said nut to a normal position, and a depressible member controlling said nut whereby the pressure of said actuating member will rotate said striker member and flex said diaphragm.

10. A signal comprising a driving shaft, a shaft rotating member movable along the shaft to rotate the shaft, a diaphragm actuating member having a toothed portion disposed substantially diametrically of the diaphragm and another portion mounted on the shaft and connected to the toothed portion and disposed in a plane to that side of the plane of the toothed portion opposite that upon which the shaft-rotating member is positioned.

11. A signal comprising a driving shaft, a shaft-rotating member movable along the shaft to rotate the shaft, a diaphragm actuating member having a portion disposed in one plane and another portion mounted on said shaft and adapted to actuate the first named portion and disposed in a plane to that side of the first named portion opposite that upon which the shaft-rotating member is positioned.

12. A signal comprising a diaphragm, a cam, a power-transmitting member co-acting

with the cam to vibrate the diaphragm, said cam having its marginal portion disposed substantially centrally of the diaphragm and its central portion dished, a shaft upon which said cam is mounted, and means in connection with the shaft and movable into and out of said dished portion for rotating said shaft.

13. A signal comprising a diaphragm, a resonator at the front of the diaphragm, a casing at the rear of the diaphragm, a shaft within the casing and rotatably mounted in substantial parallelism with the diaphragm, a diaphragm actuator mounted upon the shaft and rotating with the shaft and in a plane substantially perpendicular to the diaphragm and adapted to co-act with the diaphragm to force vibration of the latter as the former is rotated, a nut movable longitudinally of said shaft, a handle having a portion disposed outside the casing and another portion within the casing and adapted to move said nut longitudinally of the shaft, means for holding the nut from rotation when moved longitudinally in one direction whereby the shaft is rotated, and allowing free rotation of the nut when moved in a reverse direction whereby the shaft may remain stationary.

14. A signal comprising a diaphragm, a casing, a shaft rotatably mounted within the casing, a diaphragm actuator mounted upon the shaft and rotating therewith and adapted to co-act with the diaphragm to force vibration of the latter as the former is rotated, an operating member movable longitudinally of said shaft, said operating member and said shaft having coöperating parts so formed and arranged that longitudinal movement of said member forces relative rotation of said shaft and member, and means for holding said member from rotation when moved in one direction whereby rotation of said shaft is forced, and allowing rotation of said member when moved in the reverse direction whereby the shaft may remain stationary.

15. A signal comprising a diaphragm, a casing, a shaft rotatably mounted within the casing, a diaphragm actuating member having a toothed portion disposed substantially diametrically of the diaphragm and another portion mounted on the said shaft and adapted to actuate the first-named portion and disposed in a plane to one side of the toothed portion, an operating member movable longitudinally of said shaft to force relative rotation of said shaft and member, said operating member movable into the plane of the toothed portion of the actuator.

16. A signal comprising a diaphragm, a casing, a shaft rotatably mounted within the casing, a diaphragm actuating member having a toothed portion disposed substan-

tially diametrically of the diaphragm and another portion mounted on the said shaft and adapted to actuate the first-named portion and disposed in a plane to one side of the toothed portion, an operating member 5 movable longitudinally of said shaft to force relative rotation of said shaft and member, said operating member movable into the plane of the toothed portion of the actuator, 10 means for holding the said operating member from rotation when moved in one direction along the shaft, whereby the shaft is rotated, and allowing rotation of the member when moved in the other direction, 15 whereby the shaft may remain stationary.

17. A signal comprising a diaphragm, a casing, a shaft rotatably mounted within the casing, a diaphragm actuating member having a toothed portion disposed substantially diametrically of the diaphragm and another portion mounted on the said shaft and adapted to actuate the first-named portion and disposed in a plane to one side of the toothed portion, an operating member 20 movable longitudinally of said shaft to force relative rotation of said shaft and member, said operating member movable into the plane of the toothed portion of the actuator, 25 means for holding the said operating member from rotation when moved in one direction along the shaft, whereby the shaft is rotated, and allowing rotation of the member when moved in the other direction, whereby the shaft may remain stationary, a 30 handle having a portion disposed outside the casing and another portion within the casing and adapted to move said member longitudinally of said shaft, and automatic means for returning said handle and member to starting position after each shaft-rotating movement.

18. A horn including in combination a casing, a diaphragm having a bearing pin centrally thereof, a serrated member directly 45 coöperating with said bearing pin, said member being disposed so as to rotate about an axis parallel with the plane of the diaphragm, a hollow hub located in said casing and carrying said serrated member, a shaft 50 extending through said hub and attached thereto, said shaft having a helical groove extending into said hub, a push rod movable parallel with the shaft and into said hub, and means for connecting said push rod to 55 said shaft whereby a movement of the push rod in one direction will rotate the shaft.

19. A horn including in combination a casing, a diaphragm having a bearing pin centrally thereof, a serrated member directly 60 coöperating with said bearing pin, said member being disposed so as to rotate about an axis parallel with the plane of the diaphragm, a hollow hub located in said casing and carrying said serrated member, a shaft

extending through said hub and attached 65 thereto, said shaft having a helical groove extending into said hub, a push rod movable parallel with the shaft and into said hub, means for connecting said push rod to said shaft whereby a movement of the push rod 70 in one direction will rotate the shaft and whereby a movement of the push rod in the opposite direction will disconnect the same from the shaft, and a spring for moving said push rod when disconnected from said 75 operating shaft.

20. A signal comprising a driving shaft, a shaft-rotating member movable along the shaft to rotate the shaft, a diaphragm actuating member having a toothed portion and another portion mounted on said shaft and rigidly connected to the toothed portion and disposed in a plane to that side of the toothed portion opposite that upon which the shaft-rotating member is positioned. 80

21. In a signal, a diaphragm, a toothed member for vibrating the diaphragm, a driving shaft, an operating member movable lengthwise of the shaft, means for securing the toothed member to the driving shaft in 90 a plane to that side of the plane of the teeth opposite that upon which the operating member is positioned.

22. A signal comprising a diaphragm, a cam, a power-transmitting member coacting 95 with the cam to vibrate the diaphragm, said cam having its marginal portion disposed substantially diametrically of the diaphragm and its central portion dished, a shaft upon which said cam is mounted, said 100 shaft having a spirally arranged portion, and a member mounted on said shaft and movable along the shaft into and out of said dished portion of the cam.

23. A signal comprising a diaphragm, a cam, a power-transmitting member coacting with the cam to vibrate the diaphragm, said cam having its marginal portion disposed substantially diametrically of the diaphragm and its central portion dished, a shaft upon 110 which said cam is mounted, said shaft having a spirally arranged portion, a member mounted on said shaft and movable along the shaft into and out of said dished portion of the cam, and means in connection with 115 said member for rotating the shaft when said member is moved in one direction.

24. A signal comprising a diaphragm, a cam, a power-transmitting member coacting with the cam to vibrate the diaphragm, said cam having its marginal portion disposed substantially diametrically of the diaphragm and its central portion dished, a shaft upon which said cam is mounted, said 120 shaft having a spirally arranged portion, a member mounted on said shaft and movable along the shaft into and out of said dished portion of the cam, means in connection 125

with said member for rotating the shaft when said member is moved in one direction, and means allowing a free return movement of said member to starting position without 5 forcing rotation of said shaft.

25. A signal comprising a diaphragm, a resonator at the front of the diaphragm, a casing at the rear of the diaphragm, a shaft within the casing and rotatably mounted in 10 substantial parallelism with the diaphragm, a diaphragm actuator mounted upon the shaft and rotating with the shaft and in a plane substantially perpendicular to the diaphragm, and adapted to coact with the diaphragm to force vibration of the latter as the former is rotated, a nut movable longitudinally of said shaft, a handle having a portion disposed outside the casing and another portion within the casing and adapted 15 to move said nut longitudinally of the shaft, means for holding the nut from rotation when moved longitudinally in one direction whereby the shaft is rotated, and allowing free rotation of the nut when moved in a 20 reverse direction whereby the shaft may remain stationary, and means for automatically moving the nut in the reverse direction after each shaft-rotating movement.

26. A signal comprising a diaphragm, a 30 casing, a shaft rotatably mounted within the casing, a diaphragm actuator mounted upon the shaft and rotating therewith and adapted to coact with the diaphragm to force vibration of the latter as the former is rotated, a nut movable longitudinally of said shaft, a handle adapted for moving the nut along the shaft, said nut and said shaft having co-operating parts so formed and arranged that longitudinal movement of said nut 35 forces relative rotation of said shaft and nut, means for holding said nut from rotation when moved in one direction whereby rotation of said shaft is forced, and allowing rotation of said nut when moved in the 40 reverse direction whereby the shaft may remain stationary.

27. In a signal, the combination with a spiral shaft of a nut correlated with the shaft so that movement of one of said members 45 axially of the other causes a rotative movement of one of said members, a cam

correlated with one of said members so that rotation of said member causes rotation of the cam, means for moving one of said members axially of the other to rotate the cam, 55 said members each rotative with respect to said means, additional means allowing return movement of the axially movable member without rotation of the cam, a casing within which said members are mounted, 60 and a diaphragm set in vibration by rotation of said cam.

28. A signal comprising a diaphragm, a diaphragm vibrating member rotatable about an axis parallel to said diaphragm, a 65 casing inclosing said member and having its peripheral portion held rigid in respect to the peripheral portion of the diaphragm, a handle member outside of said casing and movable in the direction of the axis of said 70 diaphragm actuating member, a worm rigidly secured to one of said members extending along said axis, and a nut engaging with said worm and held against relative rotation in respect to the other member when 75 said handle is moved in one direction and free for relative rotation when said handle is moved in the opposite direction.

29. A signaling device including a diaphragm, a rotor rotatable about an axis parallel to said diaphragm, a shaft supporting said rotor and parallel to said diaphragm and having surface irregularities, a handle member movable vertically and in a direction parallel to said diaphragm, and means 80 directly engaging with said surface irregularities and including a ratchet and pawl for directly rotating said rotor in one direction during the depression of said handle and permitting continued rotation of same rotor 85 in the same direction during the return movement of said handle.

In witness whereof, I have hereunto affixed my signature, in the presence of three subscribing witnesses, this 1st day of March, 95 1912.
